STAND FOR GOLF BAGS

Francis Leigh Cox, New Berlin, Ill.

Application September 8, 1941, Serial No. 409,973

2 Claims. (Cl. 248—96)

My invention relates to supports for containers, and more especially to golf bag supports; an object being in my device to provide a convenient, simple and economical means for holding a golf bag uprightly when desired during the progress of a golf game to avoid laying the bag down on the ground when attempting to hit the golf ball.

A purpose of my invention is to provide a simple and practical as well as an automatic golf bag support, such as may require no special attention, add but little expense and require but little or no additional weight.

A particular purpose of my invention is to provide a pair of gravity operated hingedly supported standing legs for golf bag and with them a clamp operatively controlled by the longitudinal lifting strap of the bag so that the standing legs may be held snugly against the bag when not in use and automatically release to support the bag in upright position when the lifting strap is dropped after standing the bag up and leaning the same far enough to permit the standing legs to swing out in their operative position for supporting the bag.

I attain these purposes in my invention by construction thereof illustrated in the drawing, described and claimed herein.

Referring to the drawing:

Figure 1 is a side elevation of a golf bag incorporating my invention.

Figure 2 is a perspective of the same golf bag standing alone by the aid of my invention, in an upright position.

Figure 3 is a detail illustrating the manner of attachment of the pivoted clamping member in its connection with the golf bag lifting strap.

Figure 4 is a detail of another species of clamp member supported by the golf bag lifting strap in position to snugly hold the standing legs against the side of the golf bag when they are not in use.

Figure 5 is a detail of the species of clamp member shown in Figure 4 with it dropped down to a position where it will release the standing legs for a gravity swing outwardly on their supporting hinges, and showing the same secured to the golf bag lifting strap.

I shall now describe my invention and its operative advantages as I refer to the drawing which comprehensively illustrates the operating details of my invention.

For instance, in a careful analysis of the simple and efficient function of the several parts of my invention, it will be found that I utilize sci-

tifically correct mechanical principles in the operative relationship between the several parts which accomplish my purposes.

A golf bag 1 having a longitudinal lifting strap 2 normally carried over the shoulder of the player is preferably provided with an intermediate band 3 which operatively supports standing legs 4 and 5 secured to band 3 by hinge members 6 and 7 respectively. These standing legs are constructed in the manner making them a little heavier at the free end preferably, so as to permit them to quickly and easily swing outward on their hinges when they are functioning as an upright support for the bag.

There are obviously a number of ways that standing legs 4 and 5 may be made heavier at their free ends within the scope of this invention.

I prefer to set hinges 6 and 7 in their operative position on band 3 so that when standing legs 4 and 5 are clamped up against the golf bag 1 and not in use then they will toe in somewhat as shown in Figure 1; thus permitting these standing legs 4 and 5 to hingedly swing further apart at their free ends when a golf bag is set up on end and leaned over slightly toward the side of its standing legs and thus providing a neat and substantial three point support for the golf bag when the player stands it up.

It will be obvious in an analysis of my invention that any one of several forms of clamp members could be used within the scope of my invention for snugly holding standing legs 4 and 5 neatly up against the side of the golf bag when they are not in use.

I thus prefer to utilize the simplest and most practical and economical means available for this purpose.

It will be seen that when lifting strap 2 is picked up approximately at point 8 for carrying bag 1 this move will swing the bottom portion 9 of strap 2 in against the adjacent side of the golf bag 1; but when this strap is released, if the golf bag is standing, then the bottom end thereof will drop to the position shown in Figure 2.

By taking advantage of this normal action of strap 2 I find it possible to most effectively utilize a curved clamping yoke 10 held by a loop 11 carried near the bottom end 9 of strap 2 with both ends of yoke 10 pivotally supported on the sides 12 and 13 of bag 1.

It will be seen that clamp member 11 is lifted and dropped by normally lifting and dropping strap 2; so that all that is necessary for the desired manipulation of my golf bag support is to straighten up the golf bag by the hand far enough

to permit standing legs 4 and 5 to hingedly swing in against golf bag 1 and then lift the golf bag approximately at point 8 of strap 2 as is the common practice, thus causing clamp member 10 lifted by loop 11 of strap 2 to swing upwardly and snugly against the bottom free ends of the standing legs 4 and 5 where they are held as shown in Figure 1.

When the player again reaches the place where he wishes to make another drive on the golf course he will set the golf bag down on end and release strap 2 which will drop down far enough to permit clamping yoke 10 to drop below the free ends 14 and 15 of standing legs 4 and 5 permitting these free ends to swing out hingedly and support golf bag 1 in the position illustrated in Figure 2.

I am illustrating in Figures 4 and 5 a second species of clamp member for holding the standing legs 4 and 5 up against golf bag 1 when these legs are not in use, and in this species I merely provide a transverse or cross plate 16 secured to the bottom portion 9 of strap 2 instead of using the curved clamping yoke 10 for holding the free ends 14 and 15 of standing legs 4 and 5 snugly up against golf bag 1 when these legs are not in use, and this additional species of clamp falls within the scope of my invention and its operative positions are shown in Figures 4 and 5.

Having thus described the nature of my invention what I claim is:

1. In combination with a golf bag having a longitudinal lifting strap, a pair of spaced stand-

ing legs hingedly secured to the side of said bag and toeing inwardly toward each other at their bottom free ends when they are not in use, a curved clamping member pivoted on opposed sides 5 of said golf bag adjacent the bottom end thereof and a loop secured to said strap adjacent its lower end and controlled thereby for holding said standing legs snugly against side of said golf bag when the legs are not in use when lifting upwardly on said strap and for releasing the bottom free ends of said legs permitting them to swing outwardly by gravity for supporting said bag uprightly when the same is stood up on end and leaned slightly in the direction of said legs and releasing the lifting hold on said strap.

2. In combination with a golf bag having a longitudinal lifting strap, a pair of spaced standing legs hingedly secured to the side of said bag and toeing inwardly toward each other at their bottom free ends when they are not in use, a 20 clamping member secured to said lifting strap in transverse position adjacent the bottom end thereof for snugly clamping the free ends of said standing legs in their toed in position against the side of said bag and operatively disposed in position where it will drop below said standing legs permitting them to hingedly swing out by gravity when said golf bag is stood up in position to permit them to swing out and when said lifting strap is dropped.

FRANCIS LEIGH COX.
